UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

STEEL BOX-CAR.

1,293,708.

Specification of Letters Patent. Patented Feb. 11, 1919.

Application filed November 14, 1914, Serial No. 872,156. Renewed November 21, 1918. Serial No. 263,641.

To all whom it may concern:

Be it known that I, ANDREW CHRISTIANSON, a citizen of the United States, and resident of Butler, in the county of Butler and State of Pennsylvania, have invented a new and useful Improvement in Steel Box-Cars; and I do hereby declare the following to be a full, clear, and exact description thereof.

My invention relates to box cars in which the side, roof and under-frame are constructed of suitable steel beams or sections while the covering for the sides and roof is composed of plates of sheet steel secured to the framework and to each other in a manner to provide an exceedingly strong construction, and one which may be assembled with the greatest economy of material and labor. A further object of the invention is to strengthen, and at the same time, to simplify the construction of the several parts of the car, and also to provide a car, particularly, though not exclusively, adapted for carrying grain and like substances in bulk, and a construction from which a cargo of this character may be discharged, leaving the car entirely clean and clear.

With these objects in view, the invention consists in the construction and arrangement of parts, hereinafter to be described, though it is to be understood that the present embodiment of the invention here shown is presented for illustrative purposes, and that the invention broadly is not confined to such embodiment.

In the drawings, which illustrate a preferred form of the invention, Figure 1 is a side elevation of so much of the car body as is necessary to illustrate the invention; Fig. 2 is a plan view with half of the roof covering removed; Fig. 3 is a horizontal sectional view through the car body above the floor, and with the floor in part removed to more clearly show the under-frame construction in plan; Fig. 4 is an end elevation of the car body; Fig. 5 is a transverse section, the right-hand half being taken transversely through the car between the transoms, while the left-hand portion is taken transversely through the car door, the transoms being omitted to show the bolster; Fig. 6 is a longitudinal vertical section on the line 6—6, Fig. 2; Fig. 7 is an enlarged transverse sectional view taken through the side-plate and

roof; and Fig. 8 is an enlarged detail of the end construction at the floor.

55

In the embodiment of the invention herein selected for illustration and referring to Fig. 1, the side walls of the car are composed of the plates 1—1—1, extending vertically from floor to roof, and these side plates as more clearly illustrated in Fig. 3, are overlapped as at 2 and riveted together as at 3 by rivets which pass through the edges of said plates and through one flange 4 of the side-stakes 5, which extend vertically inside the car. The alternate plates adjacent the overlapping edges are riveted as at 6 to the opposite flange of the side-stakes 5; thus by a single line of rivets 3, these plates are fastened together and to the side-stakes.

60

Referring to Fig. 5, it will be seen that the lower ends of these side-wall members are riveted at 7 to the side-sills 8, while the upper ends of the side-wall plates are riveted between the downwardly extending portion 9 of the side plates proper, and at each side-stake, the downwardly extending portion 10 of a socket member 11 within which the outer end of the carline 12 hereinafter described is seated. Between these socket members, of course, the upper end of the side-wall plate 1 is riveted only to the side plate 9.

75

The end walls of the car are similarly constructed and comprise the end-wall plates 1 of the same construction as the side wall plates and secured to outside end-stakes 13 and to end plate 14 in the same manner. As shown in Fig. 3, the outer edges of the end plate 1 are flanged as at 15 and riveted to the edges of the side-wall plates, thus forming a tight joint at the corners of the car. The lower ends of the end-wall plates as shown in Fig. 4, are riveted to the upper flange 16 of a transverse angle strip whose horizontal flange 17, Fig. 3, is riveted to the tops of the longitudinal sills of the under-frame; the lower edge of the end plate being flanged as at 15a. As illustrated in the enlarged view, Fig. 7, the side plates 9 have the outwardly extending portions 19 and a depending lip 20, which not only greatly strengthens the joint between the roof and the side-walls and forms 100 a strong eave for the car roof, but carries

80

85

90

95

100

105

the drip from the roof well away from the door opening of the car. The end plate 14 as shown in Fig. 6, is of similar construction and provides a strong construction for the end of the car roof.

The roof structure consists of the transverse channel sections 21, Fig. 6, while the roof covering consists of plates 22 overlapping at their edges as at 23, said overlapped edges being secured by a single line of rivets together and to one flange 24 of the carline 21. The opposite flange of said carline is riveted to the adjacent roof plate and by the same line of rivets, supports 25 for the runway 26 are secured to the roof. From the inspection of Fig. 6, it will be seen that the carlines 21 are staggered in relation to the side-stakes 5, and the outer ends of said carline are secured and seated within the socket members 11, Figs. 6 and 7. The side-sills 8, Fig. 5 are of channel form and have a shallow lower flange 27 and a wide upper flange 28. Between these flanges are seated the outer ends of the transoms 29 which are riveted to the side-sills as at 30. The outer ends of the bolsters 32 also are seated between these flanges of the side-sills, and secured to the side-sills in the same manner. The center-sill of the car 30 may consist of a box-girder 33 to which the inner ends of the bolster members 32 and of the transoms 29 are secured. The upper faces of the bolster and of the transoms respectively, are depressed as at 34 and 35, Fig. 5, to receive the longitudinal floor-sills or supports 37 to which the floor boards 38 are secured. The outer ends of floor boards rest upon the extended or widened portions of the flanges 28 of the side-sills, and the 40 space between the ends of these floor boards and the side walls of the car is taken up with filler strips 39, which are the same width as the depth of the side-stakes and of a length equal to the distance between adjacent side-stakes. In order to prevent the accumulation of dirt or grain or other loose substance along the lower corners of the car adjacent the floor, the angle of these corners is filled with triangular strips 40 of a length equal to the distance between adjacent side-stakes. The lower flange of the transverse angle strip 16, Fig. 8, at the end of the car, extends beneath the end floor board, thus effectually closing any gap between the floor and the end-wall of the car, and if desired, a transverse strip similar to the strips 40, Fig. 5, may be extended across the end of the car to facilitate the cleaning of the corners at this point in the manner described.

The door construction comprises the following general features of construction. The frame of the door is formed of a Z-bar or section 41, to the inwardly extending flange of which the adjacent edges of shal-

low, dished panel sections 43, Fig. 1, are secured. The raised edges 44 of said panel sections being secured together by rivets 45, said edges forming channeled strengthening ribs extending transversely the door. The 70 flange 46 of the door-frame member 41 at the upper edge of the door may extend beneath the depending lip 47 of a Z-bar 48, which also forms a track or runway for the wheels 49 of the brackets 50 by which the 75 door is suspended. This depending lip 47 of the track or runway, therefore, not only forms a weather strip for the upper edge of the door, but also serves to keep the wheels of the suspending bracket on the 80 runway. The same flange 46 of the frame member of the door at the bottom, may travel in the guide-brackets 51, Fig. 5, whereby the door is held against outward swinging.

While I have herein described a particular embodiment of my invention, it is to be understood that the same may be altered in details of construction and relative arrangement of parts within the scope of the appended claims.

What I claim is:

1. In a car structure, the combination with channel-shaped, inwardly opening side-sills, and channel-shaped, downwardly opening side-plates, and channel-shaped, laterally flanged side-stakes secured to said sills and said side-plates respectively, of side wall plates having overlapping edges secured to one flange of an adjacent side-stake by a single line of rivets, the lower end of each side wall plate being secured to the web of said side-sill and the inside depending flange of said side-plate.

2. In a car structure, the combination of a channel-shaped inwardly opening side-sill, and a channel-shaped, downwardly opening side-plate, the latter having its inner flange of greater depth than its outer flange whereby said inner flange forms means for securing of side wall plates thereto, and the outer flange forms a drip member for the roof, and channel-shaped side-stakes having their ends secured to said side-sill and said side-plate respectively.

3. In a car structure, the combination with a channel-shaped side-sill and a channel-shaped side-plate, and channel-shaped side-stakes having laterally extending flanges, the ends of said side-stakes being secured respectively to said side-sill and said side-plate, channel-shaped carlines having their ends secured to said side-plates at the opposite sides of the car, the side walls of the car consisting of plates having overlapping edges secured to one flange of the adjacent side-stakes by a single line of rivets, the roof covering consisting of roof plates extending transversely from side to side of the car and having overlapping edges

85

90

95

100

110

115

120

125

130

secured to one flange of the adjacent carline by a single line of rivets.

4. In steel box car construction the combination with an under-frame including channel-shaped, inwardly opening side-sills and end-sills, channel-shaped, downwardly opening side-plates, and end carlines, channel-shaped, inwardly extending side-stakes secured to said side-sills and side-plates respectively, the side walls of the car being composed of overlapping plates having their overlapping edges secured together and to said side-stakes by a single line of rivets, and having their ends secured to the outer sides of said side-sills and to said side-plates, thereby forming flush outside side walls for the car.

5. In steel box car construction, the combination with side walls formed of overlapping vertically extending plates secured together and to the side-stakes by single lines of rivets at each joint, a roof structure consisting of channel-shaped, laterally flanged and inwardly extending carlines, the covering of said roof comprising transversely arranged, overlapping plates and having their overlapping edges secured together and to one of the flanges of a carline at each joint thereby producing a box car with flush side walls and flush roof.

6. In steel box car construction, the combination with flush side walls and flush roof covering formed respectively by over-

lapping steel plates having their overlapping edges secured together and to side-stakes and carlines respectively by single lines of rivets, of channel-shaped, downwardly opening side-plates each having a wide inner depending flange to which the side wall plates are riveted and having an outer shallow depending flange to form an eave for carrying off the drip from the roof.

7. In a steel box car construction, an under-frame including inwardly opening, channel-shaped side-sills, the upper flanges of which respectively are of extended width to form a rest for the opposite ends of the floor boards, and to seal the junction of the ends of the floor boards with the side-sills of the car, inwardly opening channel-shaped end-sills having extended upper flanges to seal the junction between the floor boards and the end-sills of the car, inwardly opening side-stakes secured to said side-sills, the side-walls of the car being composed of vertically extending plates having their vertical edges overlapping and secured together and to the side-stakes by single lines of rivets.

In testimony whereof, I the said ANDREW CHRISTIANSON, have hereunto set my hand.

ANDREW CHRISTIANSON.
